UNITED STATES PATENT OFFICE.

GUILLERMO RODRIGUEZ ZAYAS BAZÁN, OF MORON, CUBA.

LOADER FOR REVOLVERS.

Application filed November 6, 1923. Serial No. 673,193.

To all whom it may concern:

Be it known that I, GUILLERMO RODRIGUEZ ZAYAS BAZÁN, a citizen of the Republic of Cuba, and resident of Moron, Province of Camaguey, Cuba, have invented certain new and useful Improvements in a Loader for Revolvers, of which the following is a specification.

This invention relates to the operation of loading the revolvers and its object is to provide a loader for effecting the loading operation of all the bullets required at the same time. It is known that heretofore, when all the bullets in a revolver had been shot, to reload same is necessary to insert the bullets individually one at a time, which constitutes a very slow operation and keeps the user helpless during the time he is loading the arm. This invention does away with this serious disadvantage, by providing a device which in a simple manner supplies in a moment all the bullets required for loading the arm.

The invention is described with reference to the figures of the annexed drawing, in which:

Fig. 1 is a perspective view of the loader loaded with the revolver bullets.

Fig. 2 is an upper plan view of the same.

Fig. 3 is a diametral vertical section on line 3—3 of Fig. 2.

Fig. 4 is an upper plan view of the loader, with the lid and securing nut taken off.

Fig. 5 is a horizontal section on line 5—5 of Fig. 3, in the position in which are secured the revolver bullets. Fig. 6 is a view similar to that of Fig. 5 showing the bullets loose.

Fig. 7 is a detail showing a perspective view of one of the sectors which hold the revolver bullets.

And Fig. 8 is a detail showing looking from above, the washer which actuates the holding sectors of the bullets.

This loader comprises a main cylindrical body 1 closed at its upper and lower bases, which bases are provided with a plurality of circular openings 2 and 2' respectively arranged in a circle and which correspond vertically to one another for admitting freely therethrough the bullets 3 in number and position corresponding exactly with the holes of the chamber bearing the bullets of the revolver to which the loader is to be adapted. The upper base of the

cylindrical body 1 has at its upper face a circular recess 4 and a projecting ring 4' and through its solid portion a central hole 13 and a plurality of grooves or channels in 60 radial direction corresponding to the circular openings 2, and the lower base of said cylindrical body 1 has at its center a projection 15 which serves as a guide for the chamber or barrel of the revolver when 65 presenting the loader before it.

Inside the circular recess 4 of body 1 and over the radial grooves 14 of body 1 move freely sectors 5 (Fig. 7) which as shown in Fig. 6 are radially arranged and 70 each sector 5 presents on its upper face a radial rib 16 threaded on its upper face with spiral threads 16 of 45° and at its lower face each sector 5 has a rib 17 which is also radial and of smooth faces which 75 fits and slides inside each channel or groove 14 of the upper base of body 1.

On sectors 5 is mounted a washer 6 which has its lower face threaded at 16 with a left thread of 45° as sector 5, and this 80 washer fits around a stem or vertical central shaft 11 which is threaded at its upper and lower ends. The lower end screwing in the central threaded hole 13 of the upper base of body 1, and said stem 11 presents from 85 above to below to a third of its length a diametral slot 18. Washer 6 is arranged on sectors 5 so that the threads of the first mesh with the threads of the latter tending to approach or separate the same from 90 each other, according to the direction of turn of the washer.

On washer 6 is arranged a coil spring 8 (Fig. 4) which has its inner end bent in diametral straight line forming a pin 8' 95 which passes through the base of the slot 18 of stem 11 and the outer end of said spring is of hook shape 8'' for embracing a vertical pin 19 projecting from the upper face of washer 6 near the edge thereof. This 100 spring has the tension always to the right so as to maintain ready for opening the sectors to the bullets, keeping the former in contact with the latter.

On the coil spring is arranged a lid in 105 form of plate 9 slightly concave downwards and with an upper handle in cylindrical form with a corrugated crown 9', the plate 9 having at its central horizontal portion a hole 20 for receiving the pin 19 110 of washer 6, and the cylindrical body of the lid has a central hole for mounting

- on the stem 11 and besides a cylindrical recess 21 for receiving a steel bushing 7 surrounding the stem 11 and fixed thereto by a pin 22 at 90° with the slot 18 of the former, the bushing 7 adjusting on the spring 8 against the washer 6 to prevent the latter from slipping up and becoming separated from the sectors 5 and getting out of mesh with the same.
- 10 Over lid 9 is screwed on the stem 11 the nut 10 which always keeps lid 9 in position. For loading this loader, nut 10 and lid 9 are taken out and by pushing pin 19 to the right the washer 6 is caused to turn so that the same may draw the sectors 5 to the center (Fig. 6) and then the bullets 3 are introduced in the openings 2 and 2' so that the disc of the percussion cap remains above the projecting ring 4' of the upper base 20 of body 1; then pin 19 is pushed to the left for putting in tension the coil spring 8 for tightening as much as possible the arched edge of sectors 5 laterally against the lateral surface of bullets 3 beneath the discs 25 3' of the same, and in these conditions is placed the lid 9 so that the hole 20 may fit on pin 19 and nut 10 is screwed on stem 11 tightening the lid 9.
- For using the loader, the same is placed 30 against the chamber of the revolver so that the projection 15 of the loader may act as central guide, introducing the bullets 3 in the holes of the chamber of the revolver and turning slightly to the right the lid 9, 35 the washer 9, on turning with the lid, will bring back the sectors 9 to the center thus leaving free the bullets 3 which by their own weight fall into the holes of the revolver chamber.
- 40 It is obvious that the loaders can be made of different sizes according to the caliber of the bullets of the revolver and also the

details of construction of the loader can be changed without altering the spirit of essential character of the invention, which is as set forth in the appended claims.

What I claim is:

1. A loader for revolvers comprising a main body having enlarged bullet receiving holes, slidable means for frictionally securing the bullets in said holes, and rotary means for controlling and adjusting the sliding means.

2. A loader for revolvers comprising a main body having enlarged bullet receiving holes, slidable means, radially movable means for frictionally receiving the bullets in said holes, and rotary spring means actuated to control the radially movable means.

3. A loader for revolvers comprising a main body having enlarged bullet receiving holes, and also provided with radial guide grooves, slidable means on said guide grooves for frictionally holding the bullets in said holes and rotary spring means actuated to control the radially slidable means.

4. A loader for revolvers, comprising a main body having enlarged bullet receiving holes and also having a plurality of radially arranged guide grooves corresponding in number with said holes and slidable members in said grooves each with a radial rib having a spirally threaded face, said slidable members being arranged for frictionally holding the bullets in said holes, and a spring actuated revolute member having a spiral thread engaged with that of said slidable member to actuate the latter.

In witness whereof I affix my signature.

GUILLEMO RODRIGUEZ ZAYAS BAZÁN.
